(57) **CLAIM**

We claim the ornamental design for a communication module, as shown and described.

DESCRIPTION

FIG. 1 is a perspective view illustrating the top, front and right side of a design for a communication module;

FIG. 2 is a perspective view illustrating the bottom, front and right side of a design for the communication module illustrated in FIG. 1;

FIG. 3 is a top plan view thereof;

FIG. 4 is a front elevational view thereof;

FIG. 5 is a right side elevational view thereof;

FIG. 6 is a left side elevational view thereof;

FIG. 7 is a rear elevational view thereof;

FIG. 8 is a bottom plan view thereof;

FIG. 9 is a perspective view illustrating the top, front and right side of another embodiment of the design for the communication module;

FIG. 10 is a perspective view illustrating the bottom, front and right side of a design for the communication module illustrated in FIG. 9;

FIG. 11 is a top plan view thereof;

FIG. 12 is a right side elevational view thereof;

FIG. 13 is a left side elevational view thereof;

FIG. 14 is a bottom plan view thereof;

FIG. 15 is a perspective view illustrating the top, front and right side of yet another embodiment of the design for the communication module;

FIG. 16 is a perspective view illustrating the bottom, front and right side of the design for the communication module illustrated in FIG. 15;

FIG. 17 is a top plan view thereof;

FIG. 18 is a right side elevational view thereof;

FIG. 19 is a left side elevational view thereof;

FIG. 20 is a bottom plan view thereof;

FIG. 21 is a perspective view illustrating the top, front and right side of further embodiment of the design for the communication module;

FIG. 22 is a top plan view of the design for the communication module illustrated in FIG. 21;

FIG. 23 is a right side elevational view thereof;

FIG. 24 is a left side elevational view thereof;

FIG. 25 is a rear elevational view thereof;

FIG. 26 is a perspective view illustrating the top, front and right side of yet a further embodiment of the design for the communication module;

FIG. 27 is a top plan view of the design for the communication module illustrated in FIG. 21;

FIG. 28 is a right side elevational view thereof;

FIG. 29 is a left side elevational view thereof;

FIG. 30 is a perspective view illustrating the top, front and right side of another further embodiment of the design for the communication module;

FIG. 31 is a top plan view of the design for the communication module illustrated in FIG. 30;

FIG. 32 is a right side elevational view thereof; and,

FIG. 33 is a left side elevational view thereof.
